(57) **CLAIM**

The ornamental design for a stand for a handheld, as shown and described.

DESCRIPTION

FIG. 1 is a perspective view of a stand for a handheld device in a closed state, showing my new design;

FIG. 2 is a right side elevational view thereof, the left side elevational view being a mirror image thereof;

FIG. 3 is front elevational view thereof, the rear elevational view being a mirror image thereof;

FIG. 4 is a top plan view thereof;

FIG. 5 is a bottom plan view thereof;

FIG. 6 is a perspective view of s stand for a handheld device in an open state;

FIG. 7 is a left side elevational view thereof, the right side elevational view being a mirror image thereof;

FIG. 8 is front elevational view thereof;

FIG. 9 is a rear elevational view thereof;

FIG. 10 is a top plan view thereof; and,

FIG. 11 is a bottom plan view thereof.
